(57) CLAIM

The ornamental design for a front bumper for a vehicle, as
shown and described.

DESCRIPTION

FIG. 1 is a perspective view of a front bumper for a vehicle
according to my novel design;

FIG. 2 is a front view of the front bumper for a vehicle
according to my novel design;

FIG. 3 is a left side view of the front bumper for a vehicle
according to my novel design;

FIG. 4 is a right side view of the front bumper for a vehicle
according to my novel design;

FIG. 5 is a top view of the front bumper for a vehicle
according to my novel design; and,

FIG. 6 is a bottom view of the front bumper for a vehicle
according to my novel design.

The broken lines included depict environment and are not
part of the claimed design.
